UNITED STATES PATENT OFFICE.

FREDERICK M. FURBER, OF REVERE, MASSACHUSETTS, ASSIGNOR TO UNITED SHOE MACHINERY CORPORATION, OF PATERSON, NEW JERSEY, A CORPORATION OF NEW JERSEY.

MACHINE FOR INSERTING SOLE LININGS IN SHOES.

Application filed July 1, 1918. Serial No. 242,763.

This invention relates to a machine for handling sheet material and is herein illustrated as embodied in a machine for applying a lining to the bottom of the inside of a boot or shoe.

In the manufacture of boots and shoes it is customary to apply a lining to the bottom of the inside of a boot or shoe in order to protect the foot of the wearer from the 10 clenched ends of the heel-attaching nails and also, in McKay shoes, from the ridge formed by the line of stitches by which the sole is attached to the upper. Various forms of linings are employed; but, in order to 15 promote brevity, the present invention will be described as embodied in a machine for applying the linings, commonly called "heel pods" or "heel pads" which are used to cover the clenched ends of the heel-attaching 20 nails.

These linings are made of various materials, such as leather, fabric, paper and felt which, when piled in a stack, tend to 25 cling one to another so that it is difficult to withdraw a single lining or a selected number of linings from the stack, this difficulty being particularly troublesome when the linings are made partly or wholly of felt or a 30 felt-like material. According to one feature of the invention mechanism is provided for plucking, that is for pulling with sudden force, snatching or jerking a lining or similar blank from the stack. In the illustrative machine the linings are stacked in a 35 magazine and are slid one by one from the bottom thereof by a member which is caused to engage the lowermost lining and then to more suddenly from beneath the stack so as to pull out the lining very quickly. With 40 this mechanism it is possible to remove the lining or linings engaged without disturbing the remainder of the stack.

According to another feature of the invention a holder is provided shaped to support a lining or similar blank for pressure against the bottom of the inside of a shoe, or other article to which the blank is to be attached, together with means for transferring a lining from a stack or other source 45 of supply to the holder.

In the illustrative machine the holder has a supporting face which is similar in contour to that of the lining and is moved back and forth from lining-receiving position be-

neath the stack to lining-presenting position. A lining-engaging member, in the form of a picker is carried by the holder, and the movement of the holder from beneath the stack is sudden so as to pluck the lining from the stack in the manner which 55 has been referred to above. The holder then moves to lining-presenting position in which the operator presses the bottom of the inside of the shoe against it. By providing a holder shaped to support the lining while 60 it is being pressed against the shoe, all the more or less complicated mechanism which 65 would otherwise be required to lay the lining and press it into place is dispensed with.

These linings are commonly made of flexible materials most of which have a strong tendency to become wrinkled. To apply one of them, while in that condition, to the bottom of the inside of the shoe would be 70 objectionable since it would produce a ridge or bunch and consequently defeat to an extent the purpose for which it was applied. Accordingly another feature of the invention relates to means for straightening or smoothing 75 the lining or similar blank on the holder. In the illustrative machine, the holder in its movement from lining-receiving to lining-presenting position carries the lining beneath a stationary plate which exerts a drag 80 on the lining to straighten it; and thereafter means are caused to engage the lining to maintain it in its taut or straightened condition preparatory to its application to the shoe. The engaging and holding of the lining 85 also serves to prevent it from being removed from or displaced upon the holder by the action of the mechanism by which, as 90 will presently appear, cement is applied to the lining.

Further features of the invention relate to mechanism for varying the amount of cement applied to the blanks, to means for releasing the blank-engaging means when the shoe or other piece of work is pressed 95 against the holder, to means for holding a plurality of interchangeable magazines so that the desired magazine may readily be placed in operative position, and to a construction of magazine which may easily 100 be fitted to hold a blank of a given size and shape.

These and other features of the invention,

including certain details of construction and combinations of parts will be described as embodied in an illustrative machine and pointed out in the appended claims.

5 Referring now to the accompanying drawings,—

Fig. 1 is a side elevation of a machine in which the present invention is embodied;

10 Fig. 2 is a front elevation with certain parts broken away and all the magazines except the operative one removed;

Fig. 3 is an elevation of the holder;

15 Fig. 4 is an elevation of the holder in lining-receiving position beneath the stack;

Fig. 5 is an elevation of the holder in cement-receiving position;

20 Fig. 6 is an elevation of the holder in lining-presenting position with a shoe being pressed against it;

Fig. 7 is a perspective of one of the magazines with its bottom removed;

25 Fig. 8 is a perspective of one of the front plates of the magazine, and

Fig. 9 is a perspective of the bottom of the magazine.

30 Before proceeding with the detailed description of the machine, a brief description of its general mode of operation will be given. The machine normally comes to rest with the parts in the positions shown in Fig. 1, the arm 86 with its holder 7 extending horizontally in a position accessible to the operator, the magazine 9 being slightly tilted about the rod 11, and the cement 35 applier 13 being spaced above the plate 15 which has a cut-out portion beneath the applier so that the applier may move down at the proper time to apply cement to the lining. The picker pins, one of which is 40 shown at 17, and the retaining pins, one of which is shown at 19, are retracted. With the parts in these positions the operator manipulates a treadle whereupon the following movements take place. The holder 45 moves about the axis of the rod 21 until it is beneath the magazine 9 during which movement the pickers 17 are released and caused to project above the face of the holder. While the holder dwells for a 50 moment, the magazine 9 is dropped slightly by being swung in a clockwise direction about the rod 11, whereupon the pickers engage the forward portion of the lowermost lining, as shown in Fig. 4. The holder is 55 then swung suddenly from beneath the magazine 9 to pluck the lowermost lining from the stack and carries the lining beneath the plate 15 which acts to straighten, stretch or smooth the lining. The retaining 60 pins 19 are released to maintain the lining taut or straightened and another dwell of the holder occurs while the cement applier is moved down into contact with the lining, the parts being then in the positions shown 65 in Fig. 5. The holder is finally moved to

the position shown in Fig. 1 and comes to rest. A shoe is pressed against the holder, as shown in Fig. 6, to transfer the lining to the shoe and to retract the picker pins and the retaining pins. The shoe is then removed and the cycle repeated.

70 In order to provide for linings of different sizes a plurality of magazines 9 are supplied, any one of which may be placed in operative position. Each magazine is provided at its rear and somewhat above its center with a yoke 23, which hooks over the rod 11, and at its rear and near its lower end with a lug 25 which is adapted to contact with a flat bar 27. Each magazine is also 75 provided below the lug 25 with an adjustable stop 29 which, when the magazine is in operative position, is engaged at times by an intermittently operated pusher 31 fast to the end of a slide rod 33 and normally occupying the position shown by reason of the action of a coiled spring 35 and a bell crank lever 37 the upright arm of which is swiveled on the rod and the horizontal arm of which carries a roll 38 which runs on a cam 80 39. This cam is shaped so that the magazine is held for the most part in raised position, as shown, but is dropped at the proper time upon the pickers 17 as has been explained. The cam 39 is also provided with a depression which imparts a shake to the magazine after the holder has moved from beneath it so as to ensure that the stack of linings shall settle properly in the magazine under the influence of the weight 85 43.

90 In the illustrative machine the agent employed for attaching the lining to the shoe is cement. A supply of this is maintained in a receptacle 45 from which it is forced in the proper amount and at the proper time through a passageway 47 in a stationary pipe 49 and a connecting passageway in a hollow arm 51 to the applier 13. The pipe 49 and hollow arm 51 are connected by a pivot joint 53 about which the arm is 95 swung by a lever 55 pivoted at one end at 57 to the arm 51, near its center at 59 to the frame of the machine and at the opposite end at 61 to an upright cam-rod 65 which is vertically slidable. The lower end of the cam-rod carries a roll 66 which runs on a suitably shaped cam 67. The cam-rod 65, besides actuating the applier 13 in the manner described, serves also to cause, by its vertical reciprocation, the delivery of 100 cement from the receptacle 45 to the applier. To this end there is pivoted in a slot in its upper end a pawl 69 normally held in vertical position by an endless spring 71 which encircles the pawl and the rod. The pawl 105 engages a small ratchet 73 fast to a shaft 75 to which is also fast a large gear 77 the teeth of which for about ninety degrees lie close to the inner wall of the cement receptacle. A small gear 79, located at the bottom 110

tom of the receptacle and just at one side of the outlet 47, meshes with the gear 77 and is turned by it. The small gear, as well as the adjacent portion of the large gear, is partially enclosed by a casing 81 (see Fig. 2). Because of this construction and of the viscous property of the cement used, when the large gear is turned in the direction indicated by the arrow in Fig. 1, 10 a small amount of cement is squeezed into the passageway 47 and a corresponding amount forced out of the perforations 83 (see Fig. 5) in the operative face of the applicator 13. The cement is so thick that it 15 does not drip from the applicator but merely forms globules thereon so that when the applicator is brought down upon the lining, these globules are transferred to the lining. In order to permit the amount of cement delivered to be varied, the upper end of the pawl is inclined as shown and is located to contact with a set screw 85 the position of which may be varied to cause the pawl to 20 be disengaged sooner or later from the ratchet 73.

The plate 15, against which the lining is wiped by the holder, is provided with a stem which is adjustably held in a socket in the end of a stationary arm 76 by a set-screw 30 78, the face of said plate being substantially concentric with the axis of the pivot 21. This plate, as has been explained, is cut away to permit the cement applicator 13 to contact with the lining. The arm 76 also carries a small standard 178 to which is pivoted at 35 80 a yoke 82 for centering the magazine and for limiting its counter-clockwise movement. A spring (not shown) wound about the pivot and fastened at one end to the yoke and at the other to the arm tends at all times to hold the yoke in the position shown against a lug 84 on the standard 178 but permits the yoke to be swung in a clockwise direction at any time so that the 40 magazine may be removed and replaced.

The holder 7 has a face the contour of which corresponds to that of a lining, said holder being shaped to support a lining for pressure against the bottom of the inside 45 50 of a shoe. The particular shape shown is believed to be the most desirable but any shape which will afford proper support for the purpose desired may be used. Although only one holder is shown, it is intended to supply with each machine a plurality of interchangeable holders of different sizes each holder being provided with a stem 177 which fits in a socket in the arm 86 and has a slot to receive a positioning pin 87, and a notch to receive a fastening spring 89. The pickers 17 are removably fastened to the head 91 of a slidable rod 93 which is continually urged to the right, as viewed 55 60 in Fig. 6, by a coiled spring 95, said rod having pivoted thereon a pawl 97 which is

designed to engage a collar 99 on a second slide-rod 101. This rod 101, which is also continually urged to the right as viewed in Fig. 6 by a spring 103, carries a block 105 in which the retaining pins 19 are mounted. 70 To the left-hand end of the rod 101 is pivoted one end of a lever 107 which is pivoted near its center at 109 to the arm 86. A latch 111, pivoted to the arm 86 at 113 and continually urged to move angularly 75 in a clockwise direction about its pivot by a spring 115, is designed at times to engage the end of the lever 107, as shown in Figures 3 and 4, to hold the slide rod 101 in retracted position. If, at such time, the pawl 97 is in engagement with the collar 99, as shown in Fig. 3, the slide rod 93 is also held retracted; but if the pawl 97 has been disengaged from the collar 99, as shown in Fig. 4, the slide rod 93 is in its forward position in which the pickers 17 project beyond the supporting face of the holder 7. In order to disengage the pawl 97 so as to release the pickers 17, a stationary finger 117 is fastened to the frame of the machine in position to engage the tail of the pawl when the arm 86 reaches its vertical position beneath the stack, as shown in Fig. 4, the arm having a slot through which the finger may extend. In order to disengage the latch 111, a dog 119 is pivoted at 121 to a bracket 123 on the frame of the machine and is normally held in the position shown in Figs. 1 and 5 by a spring 125 80 the construction being such that it cannot move in a counter-clockwise direction from the position shown but can move in the opposite direction against the force of the spring. The purpose of this construction is to permit the upstanding lug 211 of the latch 111 to move past the dog 119 when the arm 86 is swung upwardly and to cause the dog to engage the lug and disengage the latch when the arm is swung downwardly. 85

The operation of the machine is as follows: Starting with the parts in the positions shown in Fig. 6, in which the arm 86 is at rest and the pickers 17 and retaining pins 19 are in engagement with the lining 100, the holder and the lining being 90 then accessible to the operator, a shoe is placed over the support, as shown in Fig. 6, and pressed against the lining. The effect of this pressure is to push back the slide rod 101 whereupon the latch 111 engages the end of the lever 107 and holds the slide rod in retracted position. During the pushing back of the rod 101, the collar 99 engages the pawl 97 thereby pushing back the rod 93 also. These movements of the rods effect a withdrawal or retraction of the pickers 17 and retaining pins 19 to permit the cemented lining 100 to be transferred 95 100 to the bottom of the inside of the shoe so that when the shoe is removed the lining 105 110 115 120 125

4

remains with it. The operator then manipulates a treadle to throw into operation mechanism which will presently be described whereupon the following movements take place. The arm 86 swings to the position shown in Fig. 4 in which the holder is in lining-receiving position beneath the stack and dwells there. Just before this position is reached, the finger 117 engages the tail of the pawl 97 thereby disengaging the pawl from the collar 99 and permitting the spring 95 to cause the pickers 17 to project above the face of the holder 7. The magazine 9, which has thus far been in the raised position shown in Fig. 1, is now permitted to fall until the stop 25 engages the bar 27 and the position shown in Fig. 4 is reached in which the pickers 17 are engaged with the forward portion of the lowermost lining having entered it upon an angle as shown. The arm 86 then moves suddenly from beneath the stack, whereupon the engaged lining is plucked from the stack, sliding forward without disturbing the others, and dwells beneath the cement applier 13. It will be noted that the path of movement of the lining lies in an arc of a circle tangential to the plane of the lowermost lining as it lies in the stack. Accordingly the first part of that path lies substantially in the plane of the lowermost blank as it lies in the stack and, as the lining or blank starts to move, the portion thereof which has not yet cleared the bottom plate of the magazine moves in the plane it occupied previous to its movement. During this movement the lining is wiped or dragged beneath the plate 15 and thereby smoothed or straightened; and, just before the dwell occurs, the dog 119 engages the lug 211 to disengage the latch 111 from the lever 107 and thereby release the retaining pins 19 which thereupon enter the straightened lining and in cooperation with the pickers 17 maintain the lining smooth and unwrinkled until it is attached to the shoe. While the holder dwells beneath the cut-out in the plate 15, and is held firmly by the pins 19 and pickers 17, the cement applier 13 is brought down upon the lining, as shown in Fig. 5, and then raised. The arm 86 then moves to the position shown in Figs. 1 and 6 where the shoe may be pressed against it. It should be noted that if pressure of the shoe against the lining fails to cause the pickers and retaining pins to be locked in retracted position, this result will be accomplished during the upward movement of the arm by contact of a roller 127 on the end of the rod 101 with the plate 15.

Referring now to Figs. 1 and 2, the driving shaft 129 is rotated continuously by means of a pulley 131 and has rotatably mounted upon it a cam member 133 upon

the periphery of which are the cams 39 and 67 and in the side of which is cut the cam track 135. The cam member may be connected with the shaft by a one-revolution clutch of any suitable type which is controlled by manipulation of a treadle (not shown) at the end of a treadle rod 137. The details of the illustrated one-revolution clutch form no part of the present invention, but are described and claimed in an application, Serial No. 129,468, filed August 16, 1926, which is a continuation in part of this application. The cam track 135 receives a roller mounted near the middle of an arm 137, one end of the arm being pivoted to the frame of the machine at 139 and the other end having formed thereon a segmental rack 141 which meshes with a similar rack 143 formed upon the hub of the arm 86. The cam track 135 is shaped so as to cause the arm 86 to move and dwell as has been described above.

As has been explained, the heel pods differ in size and shape; and consequently magazines of corresponding shapes and sizes should be provided. In order to provide magazines which will hold the heel pods accurately, the construction shown in Figs. 7, 8 and 9 is employed. Each magazine comprises a base or frame 151 horseshoe-shaped in cross-section, two front plates 153 and a bottom 155 cut away at its forward portion, as shown, to permit the pickers 17 to engage the lowermost blank of the stack. The frame is cast and has formed on its interior a plurality of ribs 157 which extend far enough into the interior of the horseshoe-shaped space to contact with the edge of the smallest blank. Consequently, in order to fit the magazine to hold any larger sized blank, it is necessary merely to lay such blank upon the ribs, mark the line where the edge of the blank crosses the ribs and then plane off the ribs to the marks. This construction provides a rigid magazine which will hold the stack of blanks accurately. In practice a set of magazines is made to meet the requirements of a particular factory and is supplied with the machine. In order to hold the blanks against the edges of the ribs 157, the plates 153 are screwed to the magazine as shown, and in order to support the stack the bottom 155 is screwed to the lower end of the magazine. It should be noted that the plates 153 are provided with slots 159 through which the holding screws pass so that the plates may be spaced above the bottom just sufficiently to permit one lining or other blank to be withdrawn at a time, this spacing being varied in accordance with the thickness of the blanks which are being used. As shown best in Fig. 7, two adjusting screws 161 are threaded through the upper part of the yoke 23 so as to permit

the vertical position of the magazine to be varied. This adjustment is also connected with the thickness of the blanks, and by it the extent to which the pickers 17 extend 5 into the bottom of the magazine, when the magazine is dropped upon the pickers, may be predetermined. For example, the magazine will be raised higher when thick blanks are being used than it will be when thin 10 blanks are being used. Otherwise the pickers 17 might engage more than one thin blank at a time if such blanks composed the stack. The magazines may all be hung on the rod 11; and the one which is in operative position may be removed and replaced by another at any time. In order 15 to ensure that the operative magazine shall be properly positioned by the yoke 82, each magazine has two oppositely located projections or "spots" 165 which are accurately machined and contact with the inner faces 20 of the arms of the yoke.

Although the invention has been set forth as embodied in a particular machine, it 25 should be understood that the invention is not limited in the scope of its application to the particular machine which has been shown and described.

Having thus described my invention, 30 what I claim as new and desire to secure by Letters Patent of the United States is:

1. A machine of the class described, having, in combination, means for supporting a stack of articles, and means for removing the 35 lowermost article with such celerity that the remaining articles are prevented by their inertia from being removed therewith.

2. In a machine for affixing sheets to articles, the combination with a magazine for 40 holding a stack of sheets with their edges in alignment and with adjacent blanks having their opposed faces in engagement with each other throughout substantially the entire areas of said faces, means for applying 45 adhesive to the sheets, and a rotary sheet-applying device constructed and arranged to grasp a sheet while the latter remains undisplaced with respect to the other sheets in the stack, said device being operable solely 50 through its rotative movement to separate a sheet from the stack, thereafter to present the sheet to the adhesive-applying means and later to position the sheet for application to an article.

3. In a machine for affixing sheets to 55 articles, the combination with a magazine for the sheets, of a rotary sheet-applying device constructed and arranged to act positively on the sheets during its rotative movement to pull them edgewise out of the magazine one at a time, and operative to apply them to the articles, and means for applying adhesive material to each sheet while it is 60 carried by said device.

4. A machine of the class described, having, in combination, means for supporting a stack of blanks, a holder having blank-engaging means, and means for causing sudden relative movement between the stack supporting means and the holder to take place 65 with such celerity as to cause a blank to be plucked from the stack without disturbing the remaining blanks, which are held in position by their inertia.

5. A machine of the class described, having, in combination, a magazine for a stack of linings, and a picker arm for plucking a lining from the magazine, so quickly as to break the adhesion between it and the next adjacent lining without disturbing said adjacent lining.

6. A machine of the class described, having, in combination, a magazine for a stack of linings, and a member having lining-engaging pins for separating a lining from the 85 stack and presenting it in position to be attached to the bottom of the inside of a shoe, said member having lining engaging pins for effecting the initial movement of separation.

7. A machine of the class described having, in combination, a movable magazine for a stack of articles, a movable support having a picker for engaging and holding the lowermost article in the magazine, means for holding the magazine normally in a position with the lowermost article removed from the field of operations of the picker and for effecting movement of the magazine to engage said article with the picker, and mechanism to actuate said support to 100 remove the article from the magazine and present the article in a desired position.

8. A machine of the class described having, in combination, a magazine for a stack of articles, a holder bearing picker pins and movable to and from a position beneath the magazine, and means to lower the magazine when the holder is beneath it to permit the pins to penetrate the lowermost article therein to remove it on the next movement of the holder from the stack and present it in a position outside the magazine.

9. A machine of the class described having, in combination, a magazine for a stack of articles, a holder, pickers on the holder for removing an article from the bottom of the stack, and means sequentially to operate said pickers.

10. In a machine of the class described, in combination, a support for an article, a plurality of pickers upon said support for holding an article by penetration thereof, and co-ordinated mechanisms operative at different parts of a cycle to actuate said pickers relatively to said support at different times to move the former into article-holding position.

11. In a machine of the class described, in

combination, a movable support, a plurality of article-holding pickers on said support, and means to operate each of said pickers in a different position of said support.

5 12. A device for handling an article comprising, in combination, a plurality of picker pins adapted to hold an article by penetration thereof, and means sequentially to bring said picker pins into article engaging positions.

10 13. A device for moving an article comprising, in combination, a movable support, and a plurality of sequentially operating pickers constructed and arranged to secure 15 an article to said support by penetration of the article.

14. A machine of the class described, having in combination, means for supporting a stack of linings, a holder shaped to support a lining for pressure against the bottom of the inside of a shoe, lining-engaging means carried by the holder, and means for causing relative movement between the stack supporting means and the holder to take 25 place with sufficient suddenness and to a sufficient extent to cause the blank to be snatched from the stack.

15. A machine of the class described, having in combination, a magazine for a stack 30 of linings, a holder shaped to support a lining for pressure against the bottom of the inside of a shoe, and means including the holder for snatching a lining from its original position in the stack.

35 16. A machine of the class described having, in combination, a support for a stack of linings, a holder shaped to support a lining for pressure against the bottom of the inside of a shoe, and means for transferring a lining from the stack to the holder.

40 17. A machine of the class described having, in combination, a support for a stack of linings, a holder shaped to support a lining for pressure against the bottom of the inside of a shoe, means for transferring a lining from the stack to the holder, and means for furnishing an attaching agent for the lining.

45 18. A machine of the class described having, in combination, a support for a stack of linings, a holder shaped to support a lining for pressure against the bottom of the inside of a shoe, and means for transferring a lining from the stack to the holder and for presenting the lining in position to be applied to the shoe.

50 19. A machine of the class described having, in combination, a stack of linings, a holder shaped to support a lining for pressure against the bottom of the inside of a shoe, means for transferring a lining from the stack to the holder and for presenting the lining in position to be applied to the shoe, and means for furnishing an attaching 55 agent for the lining.

20. A machine of the class described having, in combination, a source of supply of linings, a holder shaped to support a lining for pressure against the bottom of the inside of a shoe, and means for transferring a lining from the source of supply to the holder and for moving the holder into position to receive a shoe.

70 21. A machine of the class described having, in combination, a source of supply of linings, a holder shaped to support a lining for pressure against the bottom of the inside of a shoe, means for transferring a lining from the source of supply to the holder and for moving the holder into position to receive a shoe, and means for furnishing an attaching agent for the lining.

75 22. A machine of the class described having, in combination, means to support a stack of linings, a holder separate therefrom and shaped to support a lining for pressure against the bottom of the inside of a shoe, and treadle controlled means for transferring a lining from the stack to the holder.

80 23. A machine of the class described having, in combination, means to support a stack of linings, a holder separate therefrom and shaped to support a lining for pressure against the bottom of the inside of a shoe, treadle controlled means for transferring a lining from the stack to the holder, and means for furnishing an attaching agent for the lining.

85 24. A machine of the class described having, in combination, a source of supply of linings, a holder shaped to support a lining for pressure against the bottom of the inside of a shoe, and treadle controlled means for transferring a lining from the source of supply to the holder and for moving the holder into position to permit the lining to be transferred to the shoe.

90 25. A machine of the class described having, in combination, a source of supply of linings, a holder shaped to support a lining for pressure against the bottom of the inside of a shoe, treadle controlled means for transferring a lining from the source of supply to the holder and for moving the holder into position to permit the lining to be transferred to the shoe, and means for furnishing an attaching agent for the lining.

95 26. A machine of the class described having, in combination, a magazine for a stack of linings, a holder having a supporting face similar in contour to that of a lining, and means for transferring a lining from the stack to the holder and for moving the holder into position to permit the lining to be attached to the shoe.

100 27. A machine of the class described having, in combination, a magazine for a stack of linings, a holder having a supporting face similar in contour to that of a lining, means for transferring a lining from the stack to

- the holder and for moving the holder into position to permit the lining to be attached to the shoe, and means for furnishing an attaching agent for the lining.
28. A machine of the class described having, in combination, a magazine for a stack of linings, a holder separate therefrom and shaped to support a lining for pressure against the bottom of the inside of a shoe, and means for transferring a lining from the stack to the holder.
29. A machine of the class described having, in combination, a magazine for a stack of linings, a holder separate therefrom and shaped to support a lining for pressure against the bottom of the inside of a shoe, means for transferring a lining from the stack to the holder, and means for applying cement to the lining.
30. A machine of the class described having, in combination, a magazine for a stack of linings, a holder adapted to support a lining for pressure against the bottom of the inside of a shoe, and means for transferring a lining from the stack to the holder and for moving the holder into position to receive a shoe.
31. A machine of the class described having, in combination, a magazine for a stack of linings, a holder adapted to support a lining for pressure against the bottom of the inside of a shoe, means for transferring a lining from the stack to the holder and for moving the holder into position to receive a shoe, and means for applying cement to the lining.
32. A machine of the class described having, in combination, a source of supply of linings, a holder adapted to receive a lining from the source of supply and shaped to support the lining for attachment to the bottom of the inside of a shoe, and means for producing relative movement of approach and separation between the source of supply and the holder and for causing dwells in the relative movement at lining-receiving and at lining-attaching positions.
33. A machine of the class described having, in combination, a magazine for a stack of linings, a holder adapted to receive a lining from the stack and shaped to support the lining for attachment to the bottom of the inside of a shoe, and means for producing relative movement of approach and separation between the stack and the holder and for causing dwells in the relative movement at lining-receiving and at lining-attaching positions.
34. A machine of the class described having, in combination, a source of supply of linings, a holder shaped to support a lining for pressure against the bottom of the inside of a shoe, means for transferring a lining from the source of supply to the holder and for affixing it to the holder, and means for releasing the lining when a shoe is pressed against it.
35. A machine of the class described having, in combination, a source of supply of linings, a holder shaped to support a lining for pressure against the bottom of the inside of a shoe, means for transferring a lining from the source of supply to the holder and for affixing it to the holder, means for applying cement to the lining, and means for releasing the lining when a shoe is pressed against it.
36. A machine of the class described having, in combination, a magazine for a stack of linings, a holder shaped to support a lining for pressure against the bottom of the inside of a shoe, means for transferring a lining from the magazine to the holder and for affixing the lining to the holder, and means operated by pressure of the lining against the shoe for releasing the lining.
37. A machine of the class described having, in combination, a magazine for a stack of linings, a holder shaped to support a lining for pressure against the bottom of the inside of a shoe, means for transferring a lining from the magazine to the holder and for affixing the lining to the holder, means for furnishing an attaching agent for the lining, and means operated by pressure of the lining against the shoe for releasing the lining.
38. A machine of the class described having, in combination, a holder arranged to be inserted in a shoe and having a face shaped to support a blank, and means for smoothing the blank on the supporting face of the holder.
39. A machine of the class described having, in combination, a holder arranged to be inserted in a shoe and having a face shaped to support a blank, and means for stretching the blank and maintaining it taut on the supporting face of the holder.
40. A machine of the class described having, in combination, a source of supply of blanks, a holder having a face shaped to support a blank, means for transferring a blank from the source of supply to the holder, and means for smoothing the blank on the supporting face of the holder.
41. A machine of the class described having, in combination, a source of supply of linings, a holder having a face shaped to support a lining, means for transferring a lining from the source of supply to the holder, and means for smoothing the lining on the supporting face of the holder preparatory to applying it to a shoe.
42. A machine of the class described having, in combination, a source of supply of linings, a holder, means for transferring a lining from the source of supply to the

holder, and means for straightening the lining on the holder and for maintaining it in straightened unwrinkled condition.

43. A machine of the class described having, in combination, a magazine for a stack of linings, a holder upon which a lining is received and from which it may be transferred to the bottom of the inside of a shoe, said holder having a face shaped to support a lining, means for producing relative movement of approach and separation between the stack and the holder to bring them into proximity during the lining-receiving operation and to bring them into separated relation during the transfer of the lining to the shoe, and means for straightening the lining upon the supporting face of the holder.

44. A machine of the class described having, in combination, a magazine for a stack of linings, a holder upon which a lining is received and from which it may be transferred to the bottom of the inside of a shoe, means for producing relative movement of approach and separation between the stack and the holder to bring them into proximity during the lining-receiving operation and to bring them into separated relation during the transfer of the lining to the shoe, and means for straightening the lining and maintaining it taut upon the holder.

45. A machine of the class described having, in combination, a magazine for a stack of linings, a holder movable from a position adjacent to the stack in which it receives a lining to a position in which the lining may be transferred to a shoe, and means for straightening the lining and maintaining it unwrinkled.

46. A machine of the class described having, in combination, a magazine for a stack of linings, a holder movable from lining-receiving position adjacent to the stack to lining-presenting position, means on the holder for engaging one portion of a lining prior to taking it from the stack, and means acting thereafter to engage another portion of the lining to hold it taut on the holder.

47. A machine of the class described having, in combination, a magazine for a stack of linings, a holder movable from lining-receiving position adjacent to the stack to lining-presenting position, means on the holder for engaging the forward portion of a lining prior to taking it from the stack, and means acting thereafter to engage the rear portion of the lining to hold it taut on the holder.

48. A machine of the class described having, in combination, a magazine for a stack of linings, a holder movable from lining-receiving position adjacent to the stack to lining-presenting position, means on the holder for engaging one portion of a lining prior to taking it from the stack, and means

also on the holder acting thereafter to engage another portion of the lining to maintain it taut on the holder.

49. A machine of the class described having, in combination, a magazine for a stack of linings, a holder movable from lining-receiving position adjacent to the stack to lining-presenting position in which a shoe may be pressed against it, a picker mounted on the holder and arranged to engage a lining and cause it to move forward with the holder, means co-operating with the holder to straighten the lining, and means operating after the lining has been straightened to maintain it taut.

50. A machine of the class described having, in combination, a magazine for a stack of linings, a holder movable from lining-receiving position adjacent to the stack to lining-presenting position in which a shoe may be pressed against it, a picker mounted on the holder and arranged to engage a lining and cause it to move forward with the holder, means co-operating with the holder to straighten the lining, and a retaining pin operating after the lining has been straightened to maintain it taut.

51. A machine of the class described having, in combination, a support for a stack of linings, a holder, means for producing relative movement between the stack and the holder, a plurality of lining-engaging members mounted on the holder, and means for causing them to engage the lining in timed relation.

52. A machine of the class described having, in combination, a magazine for a stack of linings, a holder movable backward and forward from a position adjacent to the stack in which it receives a lining to a position in which the lining may be transferred to a shoe, a plurality of lining-engaging members mounted on the holder, and means for causing them to engage the lining in timed relation.

53. A machine of the class described having, in combination, a support for a stack of linings, a holder adapted to receive a shoe, means for transferring a lining from the stack to the holder, means for applying cement to the lining, and means for varying the amount of cement applied.

54. A machine of the class described having, in combination, a support for a stack of linings, a holder movable from lining-receiving position adjacent to the stack to lining-attaching position, means for transferring a lining to the holder, means for applying cement to the lining, and means for varying the amount of cement applied.

55. A machine of the class described having, in combination, a source of supply of blanks, means for engaging a blank and separating it from the source of supply, means for smoothing the separated blank,

and means operated by pressing the blank against a piece of work for releasing the blank-engaging means.

56. A machine of the class described having, in combination, a support for a stack of linings, means for engaging the lowermost lining and removing it from the stack, and means operated by pressing the lining against a shoe for releasing the lining-engaging means.

57. A machine of the class described having, in combination, a magazine for a stack of linings, a holder movable backward and forward from a position adjacent to the stack in which it receives a lining to a position in which a shoe may be pressed against it to transfer the lining to the shoe, a picker for engaging the lining during the forward movement, means whereby pressing the shoe against the lining moves the picker to and locks it in inoperative position, and means operating during the backward movement of the holder to move the picker to operative position preparatory to engaging another lining.

58. A machine of the class described having, in combination, a source of supply of blanks, a single means for engaging a blank and plucking it from the source of supply, means for applying adhesive to one face of the blank to secure it to a piece of work, and means for releasing the blank.

59. A machine of the class described having, in combination, a source of supply of blanks, means for engaging a blank and plucking it from the source of supply, means for furnishing an agent for attaching the blank to a piece of work, and a separate plunger moved by engagement with the work to release the blank from the engaging means.

60. A machine of the class described having, in combination, a source of supply of blanks, means for engaging a blank and sliding it from the source of supply, means for furnishing an agent for attaching the blank to a piece of work, and means operated by pressure of the work against the blank for releasing the blank-engaging means.

61. A machine of the class described having, in combination, a magazine for supporting a stack of linings, a holder, means on the holder for engaging a blank while in its original position in the stack and plucking it from the stack, means for applying cement to the lining, and means for releasing the lining to permit it to be applied to the inside of the bottom of a shoe.

62. A machine of the class described having, in combination, a magazine for supporting a stack of linings, a holder, means on the holder for engaging a blank and plucking it from the stack, means for applying cement to the lining, and means operated

by pressure of the blank against a shoe for releasing the blank-engaging means.

63. A machine of the class described having, in combination, a source of supply of blanks, a holder, blank-engaging means mounted on the holder, means for causing a blank to be engaged and for producing relative movement of approach and separation between the source of supply and the holder first to present the holder to the source of supply and then to present the blank in position to have a piece of work pressed against it, and means operated by pressing the blank against the work for disengaging the blank-engaging means.

64. A machine of the class described having, in combination, a magazine for a stack of linings, a holder adapted to support a lining for pressure against the bottom of the inside of a shoe, said holder being movable from lining-receiving position beneath the stack to lining-attaching position, a picker mounted on the holder, means for causing the picker to engage the lowermost lining when the holder is beneath the stack, means for moving the holder suddenly from beneath the stack to pluck the lowermost lining from the stack, means for applying cement to the lining, and means for withdrawing the picker from the lining when the shoe is pressed against the holder to attach the lining to the shoe.

65. A machine of the class described having, in combination, a magazine for a stack of linings, a holder shaped to support a lining for pressure against the bottom of the inside of a shoe, said holder being movable from lining-receiving position beneath the stack to lining-attaching position, a picker mounted on the holder and arranged to project above the supporting face of the holder when the holder is beneath the stack, means for lowering the stack so that the lowermost lining is engaged by the picker, means for moving the holder suddenly from beneath the stack to pluck the lowermost lining from the stack, means for applying cement to the lining, and means for withdrawing the picker from the lining when the shoe is pressed against the holder to attach the lining to the shoe.

66. A machine of the class described having, in combination, a magazine for a stack of blanks, a holder, means for producing relative movement between the magazine and the holder to position the holder with reference to the stack first to receive a blank therefrom and then to permit a piece of work to be pressed against the blank, and means operating in the first position of the parts for moving the magazine toward the holder.

67. In a lining attaching machine by the use of which linings of different shapes and sizes may be attached to shoes, a supporting

- member fast to the machine frame and adapted to receive a plurality of interchangeable magazines carrying stacks of linings of different shapes and sizes, in combination with a magazine adapted to hold a stack of linings and having a U-shaped member to seat over the supporting member, and means for removing a lining from the stack.
68. In a lining attaching machine by the use of which linings of different shapes and sizes may be attached to shoes, a supporting member fast to the machine frame and adapted to receive a plurality of interchangeable magazines carrying stacks of linings of different shapes and sizes, in combination with a magazine adapted to hold a stack of linings and having means for engaging the supporting member, means for adjusting the height of the magazine relatively to the supporting member, and means for removing a lining from the stack and presenting it in position to be applied to the bottom of the inside of a shoe.
69. A machine of the class described, having in combination, means for supporting a stack of blanks and a picker arm for snatching a blank from the stack with such celerity that it is separated from the stack without disturbing the adjacent blanks.
70. A machine of the class described, having in combination, means for supporting a stack of blanks, means for engaging the lowermost blank of the stack, and means including the engaging means for snatching the blank from the stack with such celerity that the inertia of the stack maintains the remainder of the blanks substantially in position.
71. A machine of the class described, having in combination, means for supporting a stack of blanks, means for engaging the lowermost blank of the stack, and means including the engaging means for snatching the blank from the stack with such celerity that the inertia of the stack maintains the remainder of the blanks substantially in position and for presenting it in a position accessible to the operator.
72. A machine of the class described, having in combination, means for supporting a stack of blanks of sheet material with their edges substantially in alignment, and means for engaging the side of a blank at one end of such a stack and for snatching said blank from its position in the stack to a position outside the stack in a single movement starting in a direction substantially parallel to the planes of the blanks in the stack.
73. A machine of the class described having, in combination, means for supporting a stack of blanks of sheet material with their edges in alignment and with adjacent blanks having their opposed faces in

engagement with each other throughout substantially the entire areas of said faces, an arm having a picker member movable in a rectilinear path relatively to the arm for engaging a blank at one end of such a stack while the blank continues to bear its normal stacked relation to the other blanks in the stack, means for moving the picker member relatively to the arm into position for engagement with a blank, and a cam for moving the arm to withdraw a blank from the stack and present it before the operator.

74. A machine of the class described, having in combination, a magazine for a stack of linings made of material such that the linings tend to stick to one another, and means for engaging the lowermost lining while in its original position in the stack and for removing it entirely from the stack by a single movement accomplished with such great rapidity that the adhesion of the lowermost blank to the one above it is instantly broken.

75. A machine of the class described, having in combination, a magazine for holding a stack of blanks, means for removing blanks from the stack, and means for jarring the stack to ensure that the stack shall settle properly in the magazine.

76. A machine of the class described, having in combination, a magazine for holding a stack of linings, means for exerting pressure upon one end of the stack, means for removing linings intermittently from the other end of the stack, and means for jarring the stack between the intermittent removals.

77. A machine of the class described having, in combination, a support for a stack of blanks, and a cam-oscillated arm for snatching a blank from the stack arranged to move the blank in an arcuate path the first part of which lies substantially in the plane of said blank as it lies in the stack.

78. A machine of the class described having, in combination, a magazine for supporting a stack of blanks, and a gear-oscillated arm for plucking a blank from the stack in an arcuate path the first part of which lies substantially in the plane of said blank as it lies in the stack.

79. A machine for inserting sole linings in shoes comprising a magazine for supporting a stack of linings, and means for plucking a lining from the stack arranged to move the lining in a path the first part of which lies substantially in the plane of said lining as it lies in the stack.

80. A machine for inserting sole linings in shoes having, in combination, a magazine for a stack of linings, a holder, and means for operating the holder for plucking a lining from the stack and presenting it in position to be applied to the bottom of the inside of a shoe, constructed and arranged

so to move the blank that the first part of its path of movement lies substantially in the plane of said blank as it lies in the stack.

81. In a machine of the class described, in combination, an article support, holding means for penetrating the forward portion of an article thereon, co-operating holding means for penetrating the rear portion of an article thereon, and mechanism to operate first said forward holding means and afterwards said rear holding means.

82. A combination as set forth in claim 81, in which said article-engaging means comprise picker pins.

83. A presenting apparatus for use in making shoes comprising, in combination, a support for a shoe part to be placed in a partly-finished shoe, means to position a shoe part on said support, and mechanism actuated by the pressure of the shoe to release said positioning means.

84. In a presenting apparatus, in combination, an article support, a plurality of article-engaging members to hold an article, on said support, a detent to hold each member in an inactive position, and means independently to release the several detents.

85. A presenting apparatus comprising, in combination, an article-presenting support and a picker including sequentially operable pins to hold an article on said support, said picker being constructed and arranged to be withdrawn to an inactive position by pressure against said support.

86. A presenting apparatus comprising, in combination, an article presenting support and a picker to hold an article on the support, said picker being constructed and arranged to be withdrawn to an inactive position by pressure against said support, and a safety device positively to withdraw the picker in case the pressure against the support has been insufficient to do so.

87. A presenting apparatus comprising, in combination, a magazine for articles, a support movable to deliver the lowermost article therefrom, picker pins on said support and normally below the surface thereof, and means to advance said pins at different times when the support is below the magazine to cause them to penetrate the lowermost article therein.

88. A presenting apparatus comprising, in combination, a support, article-holding members carried by said support, springs forcing said members into engagement with an article on the support, and detents to hold said members withdrawn against the pressure of the springs.

89. A presenting apparatus as defined by claim 88, in combination with means independently to release the several detents.

90. A presenting apparatus as defined by claim 88, in combination with a separate member to release each detent.

91. A presenting apparatus as defined by claim 88, in combination with means to move said plungers against the pressure of said springs, until they are locked in idle position by said detents. 70

92. A presenting apparatus comprising, in combination, a magazine for articles, a support movable beneath said magazine, an article-securing device on said support, a spring urging said device into engagement 75 with the lowermost article in the magazine, a detent restraining the device from being operated by the spring, and an abutment to release the detent as the support is moved beneath the magazine. 80

93. In a presenting apparatus, in combination, an article support having a head, a picker movable above and below said head, a plunger to move the picker, and a spring urging the plunger forward to advance the 85 picker, said plunger having a portion projecting beyond the head to be pushed for withdrawing the picker.

94. A presenting apparatus comprising, in combination, an article-supporting arm 90 movable from vertical to horizontal position, a head on said arm to support an article, a source of supply above the head when the arm is in vertical position to deliver articles thereto, and means on said arm to 95 seize articles delivered from the source of supply when the arm is in vertical position and release them when the arm is in horizontal position.

95. A presenting apparatus as defined in 100 claim 94, in combination with means to supply adhesive to articles supported by said arm when the arm is in an intermediate position.

96. In a presenting apparatus, in combination, a plurality of sets of picker-pins, to engage the same article, and means sequentially to operate said sets of picker pins. 105

97. In a presenting apparatus, in combination, a plurality of picker-pins, means to operate said pins sequentially to seize an article, and means simultaneously to withdraw said pins to release the article. 110

98. An apparatus for securing to an article a blank which is coated on one side with adhesive comprising, in combination, a supporting head for the non-coated side of a blank, and independently operable pins on said head for penetrating said blank to 115 hold it thereon. 120

99. An apparatus as defined by claim 98, in combination, with mechanism actuated by pressing an article against the adhesive-coated side of the blank for withdrawing 125 said pins to release the blank.

In testimony whereof I have signed my name to this specification.

FREDERICK M. FURBER.

CERTIFICATE OF CORRECTION.

Patent No. 1,604,160.

Granted October 26, 1926, to

FREDERICK M. FURBER.

It is hereby certified that error appears in the printed specification of the above numbered patent requiring correction as follows: Page 1, line 38, for the word "more" read "move"; page 6, line 58, claim 19, before the word "stack" insert the words "support for a"; and that the said Letters Patent should be read with these corrections therein that the same may conform to the record of the case in the Patent Office.

Signed and sealed this 12th day of July, A. D. 1927.

Seal.

M. J. Moore,
Acting Commissioner of Patents.
